LET-OFF MECHANISM FOR LOOMS

Application filed October 10, 1928. Serial No. 311,524.

The present invention relates to let-off mechanisms for looms.

One object of the present invention is to provide a let-off mechanism by which a substantially uniform tension on the warp is maintained at all times.

A further object of the invention is to provide a let-off mechanism in which the amount of let-off is accurately controlled in accordance with the diameter of the warp beam.

A still further object of the invention is to provide means whereby the warp beam may be conveniently rotated by hand from the front of the loom without interference by the let-off mechanism.

To these ends, the present invention consists of the let-off mechanism hereinafter described and particularly defined in the claims.

In the accompanying drawings, Fig. 1 is a side view of so much of a loom as is necessary to an understanding of the present invention, with the improved let-off mechanism applied thereto; Fig. 2 is a view similar to Fig. 1 showing the let-off and associated parts but on an enlarged scale; Fig. 3 is a rear view of the apparatus shown in Fig. 2; Fig. 4 is a section on line 4—4 of Fig. 2; Fig. 5 is a detail view similar to Fig. 4 but showing the pawl in raised position; Fig. 6 is a sectional detail view of the hand release mechanism; Fig. 7 is a view similar to Fig. 6 with the mechanism in released position; Fig. 8 is an end view of the hand operated release; and Fig. 9 is a section on line 9—9 of Fig. 6.

The illustrated embodiment of the invention comprises a loom frame 10 to the rear of which is suitably attached a frame 12 for supporting the warp beam and the let-off mechanism. The warp beam is shown at 14, being fixed on gudgeons 16 which are journaled in suitable recesses in the frame 12. The beam is rotated by a gear 18 which meshes with a worm 20, the latter being secured to a shaft 22 which extends forwardly and upwardly from the worm and terminates at the front of the loom in a head 24 attached thereto which is at a convenient height for access by the operator for the purpose of permitting manual rotation of the warp beam, as will presently be explained in detail.

Fixed on the shaft 22 is a ratchet 26 adapted to be intermittently rotated by a pawl 28 pivoted on a pawl arm 30 and urged toward engagement with the ratchet by a compression spring 32. A link 34 connects the pawl arm with the end of a bell crank lever 36 which is secured to a rock shaft 38 journaled in the frame 12. The upwardly extending arm 40 of the bell crank consists of a positioning arm which determines the amount of movement of the pawl in accordance with the tension on the warp, as will hereinafter be described. Secured to the rock shaft 38 and depending therefrom is a lever 42 having at its end a pin 44 received in a slot 46 in a reciprocating head 48. The head 48 is connected by a rod 50 with the lay sword 52 and is continuously reciprocated by the movements of the latter.

It will be seen that as the actuator head 48 is reciprocated by the motion of the lay sword, its engagement with the lever 42 will cause the pawl to move back and forth over the ratchet. A forward movement of the sword produces a forward or let-off movement of the pawl and a rearward beat of the sword permits the pawl to retract by gravity over the ratchet teeth, because of the lost motion connection afforded by the slot 46. The amount of let-off will depend upon the position of the pin 44, that is to say, it will depend upon the point at which the rear end of the slotted member picks up the pin, because while the lay sword undergoes a uniform movement, the pin 44 will undergo a variable movement and thereby cause a variable let-off of the warp.

It will be seen that since the pawl and ratchet are disposed in a substantially vertical plane, restoration of the pawl by gravity is permitted, thereby avoiding the necessity for a spring.

The positioning of the pin 44 with relation to the head 48, by which the amount of throw of the let-off pawl is determined, is accomplished in the following manner: In the illustrated embodiment of the invention, the whip roll 54 over which the warps pass from the warp beam is mounted in brackets 56, one at each side of the loom, which

brackets are pivoted at 58 on a stationary part of the frame. The whip roll is urged toward its rearwardmost position by the usual heavy springs 60. Depending from the rear end of the bracket 56 is a projection 62 slotted at 64 to afford an adjustable connection for an arm 66 which is bolted thereto. Pivoted to the end of the arm 66 is an adjustable link 68 which receives the threaded end of a long spring positioning rod 70. The rod 70 is downwardly inclined and near its lower end it passes freely through a spring control bushing 72. A long compression spring 74 encircles the rod 70 and bears at opposite ends against the bushing 72 and a washer 76 near the upper end of the rod. The bushing 72 has a hub 77 secured to a rock shaft 78 which extends across the loom, the compression of the spring being varied according to the angular position of the rock shaft. Inasmuch as the arm 66 is rigidly secured to the projection 62 by the bolt and slot connection, the spring 74 resists pivotal movement of the whip roll bracket 56 as the warp puts tension on the whip roll.

The arm 66 carries a pin 79 which is received in a slot 80 in the end of a pawl positioning lever 82 pivoted at 84 on the frame 12. The lower end of the lever lies in the path of the upper arm 40 of the bell crank. It will be seen that if the warp tension increases, the whip roll will be depressed and the lever 82 will be swung in a counter-clockwise direction so that the bottom end of the lever will be moved toward the right, as viewed in Fig. 2. This will permit the upper arm of the bell crank lever 40 to move toward the right and hence the pin 44 will be permitted to follow farther toward the rear of the loom upon a retracting movement of the pawl, so that on the next forward beat of the lay, the head 48 will pick up the pin 44 relatively sooner in the time of travel and hence impart an increased motion to the pawl.

The mechanism thus far described assures the proper let-off in accordance with the tension that may be placed on the warp. Thus, if the warp has for any reason been let off too slowly, the increased tension occasioned thereby will result in a wider swing of the pawl and a restoration of proper let-off conditions. Incidental variations in warp tension sufficient to require changes in the let-off 55 arise from several factors, such as variations in the rate of take-up of the finished cloth, resistance to passage of the threads through the reed and harnesses, and the like. Aside from these, however, there is a tendency toward a progressively increasing tension due to the diminution of the diameter of the warp beam as the warp is used. As the diameter decreases, it is necessary that the beam turn faster to compensate for the diminished 60 let-off for each revolution. A mechanism

as described above will satisfactorily maintain the proper feed, but it will be noted that since the feed is itself controlled by the warp tension, the increasing rate of rotation of the beam as its diameter decreases is accompanied by an increasing tension on the warp threads. It is desirable, however, especially in silk weaving, to maintain a substantially uniform warp tension at all times, and to this end the present invention affords means for varying the sensitivity of the warp tension let-off control in accordance with the diameter of the warp beam. In the preferred form of the invention, this result is attained by varying the compression of the spring 74, whereby its resistance to the movement of the whip roll is varied. To this end, the bushing 72 against which the lower end of the spring bears is varied in position in accordance with the amount of warp on the beam. A warp follower 90 having at its upper end a roll 92 to engage the warp beam is also secured to the rock shaft 78 at 94. The compression of the spring 74 tends to maintain the warp follower roll 92 in engagement with the warp. As the warp decreases in size, the follower swings in a counter-clockwise direction, as viewed in Fig. 2, thereby slightly relieving the compression on the spring 74 and permitting the whip roll bracket 56 to oscillate on its pivot 58 with greater facility. Thus, when the warp beam is relatively small, the whip roll acting under the tension of the warp is oscillated with greater ease than when the warp beam is large in size. A given degree of tension, therefore, will result in a greater amount of rotation of the beam when it is reduced in size than when it is full. Consequently, the proper feed may be maintained at all times with a substantially uniform tension on the thread. The sensitivity of the warp tension control is therefore increased as the warp beam is reduced in size.

It is desirable to provide means whereby the warp beam may be rotated by hand in either direction without interference by the let-off mechanism. The mechanism by which this result is accomplished will now be described. The head 24 which is mounted on the end of the worm shaft 22 at the front of the loom comprises a disk which is secured to the shaft 22 by a pin 100. The disk has a facing 102 of leather or other friction material adapted to bear under normal operating conditions against the face of a clutch dog 104. The dog is slidingly mounted on the shaft 22 and is maintained against rotation by a bracket 106 attached to the loom frame. The dog is recessed at 108 to embrace the squared portion of the bracket 106 whereby the dog may be free to slide on the bracket but is held against rotation. The opposite sides of the bracket are provided with projections 110 which serve as pivotal mountings for a tipping lever 112. As shown

in Fig. 9, the lever is made in the form of a hollow rectangle which surrounds the dog 104, the lower end thereof abutting a shoulder 115 on the dog. A rod 114 connects the upper edge of the rectangular lever 112 with a bell crank lever 116 which terminates at its rear end in a pawl lifter 118. A coiled compression spring 120 bearing against the upper end of the bell crank 116 normally holds the parts in the position shown in Fig. 1, the pawl lifter being out of engagement with the pawl 28. Under normal running conditions, the frictional engagement of the clutch dog 104 with the friction facing 102, affords sufficient resistance to the rotation of the shaft 22 to prevent overrunning of the ratchet when advanced by the pawl or retraction of the ratchet by the retracting movement of the pawl over it.

Pivoted at 119 on the head 24 is a hand operated cam 120 which in the position of Fig. 6, permits engagement of the dog with the disk. However, when the cam is moved to the position shown in Fig. 7, the dog 104 is pushed rearwardly, thereby rocking the lever 112 on its pivots and exerting a pull on the rod 114. This movement of the pawl crank lever swings the pawl lifter 118 into the position shown in Fig. 5, so that the lifter engages a pin 122 extending from the side of the pawl and thereby lifts the pawl out of engagement with the ratchet. The same movement of the cam disengages the dog from the friction facing and thereby relieves the friction so that the shaft 22 can be easily turned by means of the handle 124 in either direction. The engagement of the cam with the face of the dog 104 is not sufficient to resist easy manual rotation of the shaft and moreover, it maintains the dog in the position shown in Fig. 7 until such time as it is desired to restore the loom to normal operating conditions. Upon pushing the handle 124 to its original position, as shown in Fig. 6, the lifter 118 is moved to inoperative position by the spring 120 and the pawl is permitted to move into engagement with the ratchet. It will be seen that the hand control is disposed entirely at the front of the loom, where it is most conveniently accessible to the operator.

Having thus described the invention, what is claimed is:

1. A loom having, in combination, a warp beam, a let-off mechanism including a pawl and ratchet, a shaft on which the ratchet is mounted extending to and terminating at the front of the loom, a pawl lifter, a head on the front of the shaft, a handle for rotating the head, and means controlled by the handle for operating the pawl lifter.

2. A loom having, in combination, a warp beam, a let-off mechanism including a shaft extending from the warp beam to the front of the loom, gearing between the shaft and the warp beam, a pawl and ratchet for rotat-

ing the shaft, a friction device by which rotation of the shaft is resisted in normal operation, a pawl lifter, and manually operated means for simultaneously operating the pawl lifter and releasing the friction device to permit the shaft to be turned by hand.

3. A loom having, in combination, a warp beam, a let-off mechanism including a pawl and ratchet, a shaft on which the ratchet is mounted, a head secured to the shaft, a stationary friction device against which the head rotates, a pawl lifter, and manually operated means for simultaneously releasing the friction device and for actuating the pawl lifter whereby the shaft may be turned by hand.

4. A loom having, in combination, a warp beam, a let-off mechanism including a pawl and ratchet, a shaft on which the ratchet is mounted extending to and terminating at the front of the loom, a head secured to the front end of the shaft, a sliding friction dog, means for normally pressing the friction dog, into engagement with the head, a pawl lifter, a manually operated cam on the head for sliding the dog out of engagement therewith, and a connection between the dog and the pawl lifter for simultaneously operating the latter to permit rotation of the shaft by hand.

5. A loom having, in combination, a warp beam, a let-off mechanism including a pawl and ratchet, a shaft on which the ratchet is mounted extending to the front of the loom, gearing for rotating the warp beam from the shaft, a head secured to the front of the shaft, a sliding friction dog normally engaging the head, a manually operated cam on the head adapted to move the dog out of engagement therewith, a lever associated with the dog, and a pawl lifter connected with the lever whereby a manual operation of the cam releases the friction dog from the head and actuates the pawl lifter to disengage the pawl from the ratchet and permit rotation of the shaft by hand from the front of the loom.

6. A loom having, in combination, a warp beam, a let off mechanism, a roll over which the warps pass, means for mounting the roll to permit movement thereof in accordance with the warp tension, means controlled by the movement of the roll to vary the let off, a spring to resist movement of the roll, the spring being connected with the roll mounting and extending to the bottom of the loom, a warp follower, means for pivoting the follower at the bottom of the loom, and a movable abutment for the lower end of the spring adapted to be adjusted in position by the follower to vary the sensitivity of the let off control in accordance with the size of the warp beam.

In testimony whereof I have signed my name to this specification.
